(57) **CLAIM**

The ornamental design for a railway vehicle, as shown and described.

DESCRIPTION

FIG. 1 is a right side elevation view of a railway vehicle showing my new design;

FIG. 2 is a front elevation view;

FIG. 3 is a left side elevation view;

FIG. 4 is a rear elevation view;

FIG. 5 is a top plan view; and,

FIG. 6 is a front perspective view.

Portions of the railway vehicle shown in broken lines in FIGS. 1-6 form no part of the claimed design.
